PORTABLE MANIFOLDING DEVICE

John Q. Sherman, Dayton, Ohio

Application May 27, 1933, Serial No. 673,207

26 Claims. (Cl. 282—3)

This invention relates to autographic registers for producing manifolded records, and more particularly to a portable register or holder and for a supply of continuous strips of printed forms 5 which are issued from the holder in superposed registering relation with portions of transfer material interleaved therebetween, ready to receive written inscriptions.

The present device, which is of small size, compact form, and light in weight, is adapted to be readily and easily carried from place to place and is especially intended for the use of sales people, deliverymen, checkers, and others who may find it desirable to issue tickets or record 5 slips while moving from place to place.

The present manifolding apparatus comprises a box-like housing, preferably of aluminum or other light weight sheet material, having dimensions approximately equal to those of the largest 20 size packet of record material to be contained therein and provided with an adjustable top or cover which serves as a writing tablet, over which successive portions of the record strips are disposed upon withdrawal from the box or holder.

For illustrative purposes, but without necessarily limiting the invention, the printed forms are shown in the drawings impressed alternately upon opposite sides of the respective strips, the strips being issued alternately from opposite ends 30 of the box or container into overlying relation with the top or cover, forming the writing tablet. This top or cover is provided at each end with a retaining bar by which the free ends of the issued portions of the strips are clamped. The interleaved portions of transfer material are attached to a reversible carrier located within the magazine or holder for supply strips, and which also serves as a guide for the several record strips.

Although intended as a portable register or 40 manifolding device, it will be obvious that the present manifolding register may be stationarily located on top of a table or desk or may be embedded therein with its top substantially flush with the surface of a table, desk or counter, in 45 locations where the more cumbersome type of register would be highly objectionable or impractical.

The object of the invention is to simplify the construction as well as the means and mode of 50 operation of manifolding devices whereby they will not only be cheap in construction, but will be more efficient and convenient in use, of light weight and compact form, devoid of working parts or mechanism, and unlikely to get out of repair.

A further object of the invention to is provide a

simple form of packet holder for manifolding material having embodied therein a writing surface or tablet, over which the record strips may be issued, and which may be conveniently carried from place to place.

A further object of the invention is to provide an improved form of packet holder and writing tablet having stationary interleaved sheets of transfer material, past which the strips of record material are periodically withdrawn from the 10 holder or container over the writing tablet or top thereof.

A further object of the invention is to provide improved guide means for the record strips and mounting means for carbon or transfer sheets in- 15 terposed between the strips.

A further object of the invention is to provide a reversible carrier for transfer material, automatically responsive in accordance with the direction of withdrawal of the record strips from 20 the holder or container.

A further object of the invention is to provide a manifold pack that is cheap and economical to use in the register.

With the above primary and other incidental 25 objects in view, as will more fully appear in the specification, the invention consists of the features of construction, the parts and combinations thereof, and the mode of operation, or their equivalents, as hereinafter described and set forth 30 in the claims.

Referring to the accompanying drawings, wherein is shown the preferred but obviously not necessarily the only form of embodiment of the invention, Fig. 1 is a perspective view of the portable register or manifolding device, forming the subject matter hereof, with the extended portion of the record strips disposed over the writing tablet ready to receive an inscription. Fig. 2 is a perspective view, showing the terminal forms of the record strips withdrawn from the holder, ready for reversal over the top or writing tablet, the clamp or holder strip and top being in disengaged position. Fig. 3 is a longitudinal sectional view. Fig. 4 is a perspective view, with the top or writing tablet raised, and the record strips turned to expose the interleaved transfer sheets and their mounting means. Fig. 5 discloses a perspective view of one modification of the record material supply packet. Fig. 6 shows a perspective view of another modification of the record material supply packet. Fig. 7 is a detail perspective view of the transfer material folder.

Like parts are indicated by similar characters of reference throughout the several views.

Referring to the accompanying drawings, 1 is the box-like container to receive a packet 2 of superposed strips 3 which are collectively folded in reverse directions at spaced intervals into zig-zag formation.

Hinged to the box 1 is a lid or cover 4, which, when in closed position, forms a writing tablet. The ends of the box 1 are shown of slightly less height than the sides thereof to afford at each 10 end of the container an exit opening 5, through which the terminal portions of the superposed strips extend from the interior of the box or container and thence over the top or cover 4. When successive forms are printed alternately on opposite sides of the strips, as is shown in Fig. 5, then the strips will be withdrawn first from one end and then from the other end of the container 1 and exit slots 5 or other clearance are necessary at both ends of the container to permit 20 aligning adjustment. At each end of the top or cover 4 there is pivotally mounted, concentric with the hinge of the lid or cover, a clamp bar 6. The terminal portions of the lid or writing tablet 4 are preferably depressed out of the normal plane thereof, as shown in Fig. 2 to receive the clamp bars 6 to securely grip the free ends of the record strips beneath the bars 6 within the depression 7. The cover or writing tablet 4 is flanged at its free margin for overlapping engagement 25 with the side wall of the container or box 1, with which it retains its engagement by its inherent tension. The clamp bars 6 likewise overlap the margin of the cover or writing tablet 4 and engage therewith under inherent spring 30 tension to hold them in their closed or strip gripping position.

Medially disposed within the container or box 1 is a substantially U-shaped frame 8, shown in detail in Fig. 7, the upturned ends of which abut 40 upon the inner faces of the side walls of the container or box 1. Out-turned marginal fingers 9 are provided upon the frame or mounting 8, which are engageable in any one of several marginal notches 10 in the side walls of the container 45 whereby the frame 8 is engageable therewith in different positions of relative adjustment.

Pivots connected to the upturned ends of the frame member 8 are rotary heads 11 interconnected with each other by spaced rods 12 to 50 which are attached strips 13 of transfer material which extend thence out of the container or box 1 intermediate the superposed record strips 3, which latter are guided over, under and between the rods 12, as is shown particularly in 55 Fig. 4.

As the printed forms are disposed alternately upon opposite sides of the strips, as illustrated in Fig. 5, the transfer sheets 13 are double faced. These transfer strips 13 are fixedly secured to 60 the rods 12 by suitable clamping means, by pasting or by carriers mounted thereon to which the strips 13 are secured. The mounting for the transfer sheets is reversible about its pivotal connection with the frame 8 and readily accommodates itself to withdrawal of the strips in either direction from the box or container.

In using the register, after each writing operation is completed, the lid of the container or box is raised and the next succeeding set of superposed forms is withdrawn. Succeeding sets of forms are extended first about one end of the lid or writing tablet and then about the other end, thus bringing the folds of the strips into conformity with the specially provided thin edge of 75 the cover or writing tablet or associated clamp,

as may be, which by such alternation is made to always engage the interior of the fold, and by a slight pressure of the hand while adjusting the strips, such engagement of the margin or edge of the top or clamp in the fold of the strips is 5 utilized to insure accurate registry of the forms on the writing tablet. The short transfer sheets, being stationarily anchored within the container or box, readily reverse with the strips since the mounting for such transfer material is pivoted for to and fro oscillation.

By printing the forms alternately on opposite sides of the strips and then issuing the forms alternately from opposite ends of the register, the strips as originally folded will conform to the 10 margin of the writing tablet or clamp to insure registry.

With the above manifolding pack the carbon or transfer sheets must be carbonized on both sides so that each succeeding set of forms is 20 brought over the writing lid or top, first from one end of the container for one set, and then from the other end for the next set, so that the carbon paper when the forms are written upon will properly copy. When continuous length interleaved carbon strips are used, the pack is placed in the container and one set of forms extended over the edge of the container, the lid 4 is closed down and the forms placed in writing position over the writing lid 4, being held in position by 25 the clip or clamp bar 6 at the opposite edge. After the forms have been written upon they are released from their position over the writing tablet to permit the opening of the lid 4 and then, while still grasping the forms, the lid is removed, the next set of forms lifted from the container, after which the lid is closed down, the unwritten set of forms placed and clamped thereon, and the written forms detached. If desired, the written forms may be detached prior 40 to the clamping of the succeeding unwritten forms. Where the continuous form carbon is used, the carbon strips are preferably provided with tabs 14 so that the carbon sheets can be easily withdrawn from the forms after said forms 45 have been detached.

Where continuous transfer strips are not interleaved, the short carbon sheets 13, which are anchored upon the spaced rods 12 carried by the rotary heads 11, must be carbonized on both sides 50 as in continuous length carbon strips. When the forms are alternately drawn from one side of the container or the other, the assembly of the carbon sheets 13 will turn over to follow the record sheets in either direction. In using this assembly device, the printed forms are drawn, preferably while the lid of the container is open, through the assembly of stationarily anchored carbon sheets 13 until the printed forms are sufficiently withdrawn from the container to fit over the outside of the lid or writing tablet 4. The lid is then closed down and the unwritten forms placed in position thereon and clamped in position by the clamp near the free end of the strips, after the written forms are detached, the clamp at the 60 other end forming a continuation of the writing surface.

In Fig. 6, short carbon sheets 13 have been shown interleaved between the printed record material adapted for use in the modification disclosed in Figs. 4 and 7.

The various copies of the written forms, after being detached, are preferably, in part or whole, stored on the under side of the container and held in position by a clip leaf holder 15 hinged to the 75

container at 16 and biased against the bottom of the container by a suitable spring not shown.

Cross reference is made to copending companion applications, Serial No. 729,034, filed June 6, 5 1934, Serial No. 677,629, filed June 26, 1933, Serial No. 741,578, filed August 27, 1934, Serial No. 741,579, filed August 27, 1934, and Serial No. 741,580, filed August 27, 1934.

From the above description it will be apparent 10 that there is thus provided a device of the character described possessing the particular features of advantage before enumerated as desirable, but which obviously is susceptible of modification in its form, proportions, detail construction and arrangement of parts without departing from the 15 principle involved or sacrificing any of its advantages.

While in order to comply with the statute, the 20 invention has been described in language more or less specific as to structural features, it is to be understood that the invention is not limited to the specific features shown, but that the means and construction herein disclosed comprise the preferred form of several modes of putting the 25 invention into effect, and the invention is therefore claimed in any of its forms or modifications within the legitimate and valid scope of the appended claims.

Having thus described my invention, I claim:

30 1. A register for use with superimposed continuous strips of printed forms having succeeding forms printed on opposite sides so that when the strips are stacked in zigzag relation the forms all face the same direction, said register including a compartment for storing a pack of the zigzag folded strips, a writing tablet mounted on said container forming a lid therefor, said container and lid being arranged to provide clearance at either end to permit the sheets to extend from the 40 container over the lid from either end thereof.

45 2. In a register for use with superimposed continuous strips of printed forms having succeeding forms printed on opposite sides so that when the strips are stacked in zigzag relation the forms all face the same direction, the combination of a container, for storing a pack of the folded strips, said container having openings in opposite ends with a lid for the container over which the succeeding forms are drawn from opposite ends in 50 the writing position through the openings in either end, said lid being pivotally attached to the container.

55 3. An autographic register for use with superimposed printed strips having succeeding forms printed on the opposite sides thereof so that when the strips are stacked in zigzag relation they all face the same direction, said register including a container for said stack of strips, said container having spaced openings through which the strips 60 may extend, and a lid therefor arranged to have succeeding forms withdrawn from opposite ends of the lid through said openings so as to present the succeeding printed forms facing in the same direction.

65 4. An autographic register for use with superimposed printed strips having succeeding forms printed on the opposite sides thereof so that when the strips are stacked in zigzag relation they all face the same direction, said register including 70 a container for said stack of strips having spaced exit openings extending therein so that succeeding forms may be withdrawn from opposite ends thereof to present the succeeding printed forms facing in the same direction, and a writing table 75 associated with said container over which with-

drawn portions of the strips may be disposed face uppermost.

5 5. An autographic register for use with superimposed printed strips having succeeding forms printed on the opposite sides thereof so that when the strips are stacked in zigzag relation they all face the same direction, said register including a container for said stack of strips, a tablet associated with said register having a clearance passage under each end into the container, clamping 10 members associated with the ends of the tablet for clamping the free ends of the record strips withdrawn from either end as they overlie the table.

15 6. In a register for use with superimposed printed strips having succeeding forms printed on the opposite sides thereof so that when the strips are stacked in zigzag relation they all face the same direction, the combination of a writing tablet arranged to receive forms from either end, 20 and clamping members associated with the ends thereof, the writing tablet being shaped to receive the clamping members whereby one of the clamping members presents a smooth writing surface 25 flush with the writing surface of the tablet when the other is used in clamping the strips.

7. In a register for use with superimposed printed strips having succeeding forms printed on opposite sides thereof so that when the strips are stacked in zigzag relation they all face the same direction, a writing tablet and a pair of clamps mounted, one at each end of the tablet, the writing tablet being so shaped that as the forms are extended over the tablet from either end thereof the free ends of the forms may be 30 clamped by one clamp while the other clamp extends the writing surface of the tablet.

35 8. An autographic register for use with superimposed printed strips having succeeding forms printed on the opposite sides thereof so that when the strips are stacked in zigzag relation they all face the same direction, said register including a container for said stack of strips, a tablet associated with said container having passages underneath either end thereof so that the forms may be 40 drawn over either end so as to present the printed surface and permit the alignment of the forms at the folds against the edge of the tablet when in closed position, and a carbon sheet holder 45 mounted in said container for supplying transfer material to the strips.

50 9. An autographic register for use with superimposed printed strips having succeeding forms printed on the opposite sides thereof so that when the strips are stacked in zigzag relation they all face the same direction, said register including a receptacle to receive a packet of said zigzag folded strips, and having exit openings in its opposite ends through which succeeding portions of the strips may be alternately withdrawn from opposite ends of the receptacle, a writing tablet 55 overlying the receptacle over which the succeeding withdrawn portions may be reversely folded in alternating directions to writing position according to the end of the receptacle from which they are withdrawn and means beneath the writing tablet for presenting transfer material in 60 manifolding relation with the withdrawn portions of the strips in accordance with the disposition thereof in writing position.

65 10. An autographic register for use with superimposed printed strips having succeeding forms printed on the opposite sides thereof so that when the strips are stacked in zigzag relation they all face the same direction, said register including 70

- means for supporting a stack of strips, a tablet overlying said supported stack of strips, and reversible means for supplying transfer sheets from either end of said tablet.
5. 11. An autographic register for use with superimposed printed strips having succeeding forms printed on the opposite sides thereof so that when the strips are stacked in zigzag relation they all face the same direction, said register including 10 means for supporting a stack of said strips, a tablet overlying said supported stack, said tablet having clearance adjacent its ends so that the strips may be fed thereto from either end thereof, and means for supplying transfer material intermediate the record strips, including one or more supporting bars rotatably mounted.
12. An autographic register for use with superimposed printed strips having succeeding forms printed on the opposite sides thereof so that when 20 the strips are stacked in zigzag relation they all face the same direction, said register including a container for said stack of strips having openings at its opposite ends through which succeeding portions of the strips may be alternately withdrawn, a lid therefor arranged to have succeeding forms withdrawn thereover from opposite ends thereof, said lid being arranged to register folds of the forms at either end, and clamping members associated with the opposite ends thereof, 25 said clamping members being arranged to clamp the free ends of the strips brought in registry.
13. A packet holder for manifolding material comprising a box-like container to receive a 30 packet of superposed continuous record strips, and from which the strips may be withdrawn alternately at opposite ends of the container, a cover for the container forming a writing tablet over which the withdrawn portions of the strips are reversely extended, a clamping member for 35 temporarily securing the free ends of the reversely extended strips upon the writing tablet, and a reversible mounting for strips of transfer material located within the container from which connected portions of transfer material may extend thence exteriorly of the container and over the top thereof intermediate the extended portions of the strips.
14. A packet holder for manifolding material comprising a box-like container to receive a 40 packet of superposed continuous record strips, and from which the strips may be withdrawn alternately at opposite ends of the container, a cover for the container forming a writing tablet over which the withdrawn portions of the strips are reversely extended, a clamping member for 45 temporarily securing the free ends of the reversely extended strips upon the writing tablet, a pivotally mounted carrier for strips of transfer material including oscillatory transverse guides for the superposed strips and to which the strips of transfer material may be connected, said strips being adapted to extend thence exteriorly of the container and over the writing tablet intermediate the extended portions of the record strips.
15. In a manifolding device, a box-like container for a packet of superposed strips of record material having at its opposite ends exit openings 50 through which the terminal portion of the assembly of strips may be alternately extended, a cover for the box forming a writing tablet over which the extended portions of the strips may be laid first in one direction and then in the other, 55 clamp means at the opposite ends of the cover adapted to engage the extended free ends of the strips, and a reversible carrier for transfer material interiorly of the box-like holder from which portions of transfer material may extend beyond the container and over the top thereof intermediate the extended portions of the strips.
16. In a manifolding device, a box-like container for a packet of superposed strips of record material having in its end an exit opening through which the strips may be progressively withdrawn, a cover for the container forming a writing tablet over which the withdrawn material may be extended, means for temporarily clamping the free ends of the strips upon the writing tablet, a plurality of oscillatingly mounted supports within the container forming guides for the strips and to which strips of transfer material may be connected, and from which the transfer material extends thence exteriorly of the container and over the writing tablet between the extended portions of the strips.
17. In a portable autographic register for use with continuous superposed strips of record material reversely folded at spaced intervals into zigzag formation, a container for a packet of 25 such strips, having at least one opening through which succeeding portions of the strips may be withdrawn, a cover therefor forming a writing tablet over which the withdrawn portions of the strips may be extended in writing position, and a 30 pair of spaced rods extending across the container and pivoted on an intermediate axis at a substantially mid-length point of the container at least one of which is adapted to guide at least one of the strips in its passage to the withdrawal opening.
18. In a portable autographic register for use with continuous superposed strips of record material reversely folded at spaced intervals into zigzag formation, a container for a packet of 40 such strips, having at least one opening through which succeeding portions of the strips may be withdrawn, a cover therefor forming a writing tablet over which the withdrawn portions of the strips may be extended in writing position, and a swinging guide member having two positions and located within the container transversely of the strips adapted to guide at least one of the strips in its passage to the withdrawal opening, 45 said guide member swinging from one position to the other when one form length is removed and another advanced into writing position.
19. In a portable autographic register for use with continuous superposed strips of record material reversely folded at spaced intervals into 55 zigzag formation, a container for a packet of such strips, having at least one opening through which succeeding portions of the strips may be withdrawn, a cover therefor forming a writing tablet over which the withdrawn portions of the strips may be extended in writing position, a pair of relatively spaced guide members within the container extending transversely of the strips and pivoted on an intermediate axis about which the guide members have unison swinging motion, at 60 least one of which is adapted to guide at least one of the strips in its passage to the withdrawal opening.
20. In a portable autographic register for use with continuous superposed strips of record material reversely folded at spaced intervals into 70 zigzag formation, a container for a packet of such strips, having at least one opening through which succeeding portions of the strips may be withdrawn, a cover therefor forming a writing 75

- tablet over which the withdrawn portions of the strips may be extended in writing position, with portions of transfer material interleaved therebetween, and a pair of spaced rods extending 5 transversely across the container at a substantially mid-length position adapted to guide at least one of the strips and comprising attachment means for the transfer material which is connected thereto.
- 10 21. In a portable autographic register for use with continuous superposed strips of record material reversely folded at spaced intervals into zigzag formation, a container for a packet of such strips, having at least one opening through which succeeding portions of the strips may be withdrawn, a cover therefor forming a writing tablet over which the withdrawn portions of the strips between which portions of transfer material may be interleaved, may be extended in writing 15 position, and a swinging mounting located within the container to which the interleaved transfer material may be anchored, by the swinging motion of which said mounting and transfer material is reversible relative to the container.
- 20 22. In a portable autographic register for use with continuous superposed strips of record material reversely folded at spaced intervals into zigzag formation, a container for a packet of such strips, having at least one opening through which succeeding portions of the strips may be withdrawn, a cover therefor forming a writing tablet over which the withdrawn portions of the strips, having therebetween portions of transfer material, may be extended in writing position, and a 25 plurality of relatively spaced mounting rods for the transfer material within the container extending transversely of the strips and pivoted upon an intermediate axis about which the mounting members have swinging motion.
- 30 23. In a register for use with superposed printed strips having succeeding forms printed on opposite sides thereof so that when the strips are stacked in zigzag relation they all face in one direction, a writing tablet over either end of which the strips may be extended into writing position thereon, and strip engaging means associated with the tablet and engageable with the free ends of the strips alternately at opposite ends of the 35 tablet by which the strips are stationarily held at the end of the table opposite that over which they are extended thereonto.
- 40 24. An autographic register for use with superimposed printed strips having succeeding forms printed on the opposite sides thereof so that when the strips are stacked in zigzag relation they all face the same direction, said register including means for supporting a stack of strips in such relation that the succeeding portions thereof may be withdrawn alternately from opposite ends of the stack, a tablet overlying said supported stack of strips, said tablet having its ends arranged in substantially aligned relation with opposite edges of the stack so as to be arranged to receive strips from either end of the stack depending upon the 45 side on which the printed forms appear, means for presenting transfer material to said tablet in interleaved relation with the strips from either end of the tablet.
- 50 25. A dispensing holder for use with a packet of superposed continuous record strips having successions of forms printed thereon, the succeeding forms of the several strips being printed on adjoining portions alternately on the opposite sides of the same strips and approximately registered with forms printed on corresponding sides of other strips of the assembly, said packet holder having an exit at each end through which the terminal portions of the strips may be alternately withdrawn, and a reversible carrier for short 55 lengths of transfer material interleaved between the terminal portions of the strips located medially within the packet holder and enabling the sheets to be reversed with alternation of the terminal portions of the strips.
26. A packet holder for use with a plurality of superposed continuous strips, each comprising a series of printed forms upon adjoining sections of the strips, these succeeding forms of each appearing on opposite sides of the same strips, said holder having an exit opening at each end thereof through which the strips may be extended alternately into reverse positions upon the top of the holder, a mounting therein for relatively short lengths of transfer material interleaved between the terminal portions of the strips upon which the transfer sheets are reversible to agree with the alternate disposition of the terminal portions of the strips.

JOHN Q. SHERMAN. 50
